Primary Examiner — David G Muller*Assistant Examiner* — Christina Gabrielle Cosden(74) *Attorney, Agent, or Firm* — Patent Technologies, LLC; Robert D. Gunderman, Jr.(57) **CLAIM**

The ornamental design for a fastening device locking piece, as shown and described.

DESCRIPTION

FIG. 1 is a bottom plan view of a fastening device locking piece showing my new design;

FIG. 2 is a bottom perspective view of the fastening device locking piece of FIG. 1;

FIG. 3 is a second bottom perspective view of the fastening device locking piece of FIG. 1;

FIG. 4 is a top perspective view of the fastening device locking piece of FIG. 1; and,

FIG. 5 is a second top perspective view of the fastening device locking piece of FIG. 1.
